UNITED STATES PATENT OFFICE.

CHARLES E. WILSON, OF MUSKEGON, MICHIGAN, ASSIGNOR TO THE SHAW-WALKER COMPANY, OF MUSKEGON, MICHIGAN, A CORPORATION OF MICHIGAN.

BASE FOR FILING-CABINETS AND THE LIKE.

1,080,874.

Specification of Letters Patent.

Patented Dec. 9, 1913.

Application filed April 22, 1912. Serial No. 692,431.

To all whom it may concern:

Be it known that I, CHARLES E. WILSON, a citizen of the United States, residing at Muskegon, in the county of Muskegon and 5 State of Michigan, have invented new and useful Improvements in Bases for Filing-Cabinets and the like, of which the following is a specification.

My present invention relates to bases for 10 filing cabinets, and the like, and its object is to provide an improved base of that character, which will be readily adjustable to cabinets of different sizes and which will be extensible to support a varying number 15 of such cabinets. This object is attained by, and my invention is preferably embodied in, the base hereinafter described, illustrated by the accompanying drawings, in which:

20 Figure 1 is a view in perspective of said base; Fig. 2 is a bottom plan view of the same; Fig. 3 is a top plan view of a supplementary body member thereof, etc.; Fig. 4 is a view in perspective of one of the connecting bars; Fig. 5 is a like view of one of the cabinet-holding stops; Fig. 6 is a like 25 view of a cabinet supported on said base; Fig. 7 is a like view, enlarged, of a portion of the same, and Fig. 8 is a like view of two 30 cabinets supported on said base, certain parts in said last three views being broken away.

The base has two body members, 1, 2, each provided with two legs 3, and adapted 35 to be securely held by suitable means at varying distances apart, in order to accommodate cabinets, etc., of different widths. Such means for holding the body-members in desired relative adjustment preferably 40 comprises a pair of metal connecting bars 4, each slotted longitudinally toward both ends, as at 5, through which slots bolts 6 carried by the body member are adapted to freely pass. Wing nuts 7 are threaded on 45 these bolts and are adapted to engage the connecting bars to clamp them to the body members, and thus secure the proper ad-

justment of such members relatively to each other. When it is desired to support two cabinets 8 on the base, as shown in Fig. 8, 50 a supplementary body member 9 having connecting bars and in all respects similar to one of the body members 1, 2, is added to the base, by loosening the nuts on body member 2 and inserting the bolts of said 55 member into the outward slots of the connecting bars carried by the supplementary body member 9, and after adjusting the three body members 1, 2 and 9, so that the middle legs 10 (Fig. 8) are directly below 60 the meeting line of the two cabinets, the nuts are tightened, the nuts of the body member 2 clamping the connecting bars extending to both the body members 1 and 9. Suitable stops 11 carried by the body mem- 65 bers are adapted to abuttingly engage the inner edges of the stiles 12, as shown in Figs. 6, 7 and 8, to hold the cabinets against forward or backward movement. To accommodate stiles of different thickness in 70 the direction of the front and back of the cabinet, the stops may be pivoted eccentrically on the body members, as at 13, so as to be turned to present the short or the long arm for engagement with the stiles. 75

Where two cabinets are to be joined as in Fig. 8, the adjacent side pieces 14 are removed by loosening the screws 15, and the cabinets are then connected as by screws 16 in the stiles 17. 80

Not confining myself to the details of construction shown and described, I claim:

1. In a device of the character described, three body members each provided with legs, two of said members having each a 85 bar connected thereto provided with a longitudinal slot, and the third said member being arranged between said other members and having a threaded bolt adapted to move in the slots and provided with a nut adapt- 90 ed to clamp the bars to the said third member, to adjustably connect the said members at a desired distance apart.

2. In a device of the character described,

three body members, two of said members having each a laterally-extending bar, and the third body member being arranged between said other members and having means for clamping both the bars to said third body member, to adjustably connect the said members at a desired distance apart.

In testimony whereof I have hereunto set my hand in presence of two subscribing witnesses.

CHARLES E. WILSON.

Witnesses:

CHAS. M. WILSON,
CYRUS W. RICE.
